COMBINED COASTER AND ASH TRAY

John A. Hornyak, Hammond, Ind.
(P.O. Box 728, Whiting, Ind. 46394)

Filed Feb. 16, 1967, Ser. No. 5,835

Term of patent 14 years

(Cl. D85—2)

FIG. 1

FIG. 2

FIG. 3

FIG. 5

FIG. 4

FIG. 1 is a perspective view of a combined coaster and ash tray showing my new design;

FIG. 2 is a top plan view;

FIG. 3 is a left end elevational;

FIG. 4 is a right end elevational view; and

FIG. 5 is a rear elevational view.

The essential features of my design are shown in full lines, the drinking glass shown by broken lines in FIG. 5 being for illustrative purposes only.

I claim:

The ornamental design for a combined coaster and ash tray, as shown and described.
